US0D1038392S

(12) **United States Design Patent** (10) **Patent No.:** **US D1,038,392 S**
(45) **Date of Patent:** **** Aug. 6, 2024**

(54) **TRANSCATHETER DEVICE**

(71) Applicant: **TAU-PNU MEDICAL CO., LTD.,**
Busan (KR)

(72) Inventor: **June Hong Kim**, Busan (KR)

(73) Assignee: **TAU-PNU MEDICAL CO., LTD.,**
Busan (KR)

(**) Term: **15 Years**

(21) Appl. No.: **29/838,852**

(22) Filed: **May 16, 2022**

Related U.S. Application Data

(62) Division of application No. 29/733,461, filed on May 1, 2020, now Pat. No. Des. 956,220.

(57) **CLAIM**

I claim, the ornamental design for a transcatheter device, as shown and described.

DESCRIPTION

FIG. 1 is a front perspective view of a transcatheter device in accordance with the present invention;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 5 Drawing Sheets
